(57) **CLAIM**

The ornamental design for a "core of a wearable information terminal," as shown and described.

DESCRIPTION

FIG. 1 is a front, right perspective view of a core of a wearable information terminal in accordance with our new design;

FIG. 2 is a front elevation view thereof;

FIG. 3 is rear elevation view thereof;

FIG. 4 is a top plan view thereof;

FIG. 5 is a bottom plan view thereof;

FIG. 6 is a right-side elevation view thereof; and,

FIG. 7 is a left-side elevation view thereof.

(Continued)

The broken lines shown in drawings depict portions of the core of a wearable information terminal that form no part of the claimed design.

1 Claim, 5 Drawing Sheets
